TOWEL DISPENSING APPARATUS

Remain De Bersaques, Seattle, Wash., assignor
to Steiner Sales Company, Chicago, Ill., a cor-
poration of Utah

Application May 17, 1934, Serial No. 726,085

12 Claims. (Cl. 312—38)

This invention relates to improvements in apparatus for dispensing toweling and more particularly to a type of apparatus in which a loop of toweling is normally maintained outside of the cabinet, and in which towel delivery is obtained as the result of pulling of the towel by the user, and in which the soiled toweling is taken up by a roll, also as the result of such pulling of the towel by the user. The two rolls normally traveling at an equal speed, the depending loop is maintained at a predetermined length.

An object of the invention is to provide means for normally operating the feed roll and take-up roll at equal speed and further to provide means to be automatically conditioned as a result of such normal operation for subsequently automatically simultaneously rotating the feed roll and take-up roll to the end that the depending loop and the entire unused end portion of the towel is drawn wholly within the cabinet, so that it will be no longer visible or accessible to the user.

A further object is to provide means for automatically rotating the feed roll and take-up roll at equal yet accelerated speed to take up the depending loop and unused end portion of the towel, thus eliminating the danger of catching the hand of the user between the bottom of the cabinet and the web of the toweling.

Another object is to obtain automatic and accelerated action of take-up and feed rolls by means of a spring, in such manner that the spring is gradually put under tension and energy is automatically stored during the towel dispensing period, and further, to provide means by which this energy can be released when the roll of clean toweling is exhausted.

Another object is to wind or tension the spring by means including a train of gears or equivalent driving means for the rolls, a dog mounted eccentrically for oscillatory movement on the shaft of the take-up roll, said dog adapted to engage a ratchet mechanism mounted to gradually tension the spring upon each rotation of the take-up roll.

Another object is to provide means for locking the take-up roll and feed roll against rotation should a maliciously inclined person cut the towel web and endeavor to remove the toweling from the cabinet.

A further object is to provide a stop mechanism which is operative during the normal towel dispensing period but becomes inoperative upon the actuation of the mechanism for automatic and

accelerated action of the take-up and feed rolls to draw the depending loop into the cabinet.

Features include all details of construction along with the broader ideas of means inherent in the disclosure or illustrated or described therein.

Objects, features and advantages of the invention will be set forth in the description of the drawings forming part of this application, and in said drawings,

Fig. 1 is a vertical transverse sectional view on the line 1—1 of Fig. 6 through a towel cabinet embodying my invention when there is remaining a substantial supply of clean toweling, and with the normal amount of looped toweling beneath 15 the cabinet;

Fig. 2 is a vertical sectional view on the line 2—2 of Fig. 6, illustrating the driving gear train for the feed and take-up rolls and the associated spring winding mechanism and also showing the 20 trip mechanism with all parts positioned in correspondence to those in Fig. 1 or the normal towel dispensing period;

Fig. 3 is a detail plan sectional view on the line 3—3 of Fig. 2 illustrating the spring windup and 25 associated clutch mechanism and the trip mechanism for moving said clutch, all parts positioned as when the spring is being put under tension;

Fig. 4 is a partial detail sectional view similar to Fig. 3 showing the actuation of the trip mechanism whereby the spring is released to actuate the feed and take-up rolls to draw the towel loop into the cabinet;

Fig. 5 is a detail view of the lower portion of the trip mechanism just before actuation of said 35 mechanism upon exhaustion of the clean towel roll;

Fig. 6 is a detail sectional view on the line 6—6 of Fig. 2 illustrating the relative position of the take-up roll, the clean and the soiled towel rolls, 40 the spring and spring winding mechanism and showing these various elements supported within and upon the inner pivoted compartment of the main cabinet;

Fig. 7 is a detail sectional view similar to Fig. 2 45 but with the parts positioned as after tripping has taken place;

Fig. 8 is a detail sectional view on the line 8—8 of Fig. 6 showing the eccentrically mounted dog engaging the ratchet for tensioning the spring 50 and showing a latch for holding the spring in tension;

Fig. 9 is a view similar to Fig. 8 but showing the parts positioned as when after tripping;

Fig. 10 is a vertical sectional view on the line 55

10—10 of Fig. 6 showing the stop mechanism and its associated timing element and also the means provided for preventing rotation of the take-up roll; and

5 Fig. 11 is a detail sectional view similar to Fig. 10 but showing the parts positioned to prevent rotation of the take-up roll as when the towel web has been severed.

This invention is herein shown as applied to a 10 wall type towel dispensing cabinet but is applicable to other forms and types of towel dispensing apparatus.

Referring first to Fig. 1, numeral 2 indicates the outer casing of the cabinet. This casing is 15 provided with the usual door 3, side walls 4, rear wall 5 and top 6. Attached to the rear wall 5 of the casing is a bracket 7 which forms part of a means for smoothing out and tensioning the soiled towel before it reaches the soiled towel roll. 20 This bracket 7 also provides means for limiting the rearward movement of the inner swing housing.

Within the casing 2 is an element, referred to herein as the swing-housing. This housing is 25 formed by two side plate members 8 and 9 cross-connected at their lower portions by a plate having a vertical portion 11 and a horizontal portion 12, the latter portion forming a false bottom of the housing and providing a support for 30 a roll of clean toweling 14. The horizontal portion 15 is secured to the side plate members 8—9 and the horizontal portion 12 as shown and extends rearwardly and has its rearward edge 16 terminating adjacent the rear wall 5 of the outer 35 casing and cooperates with the bracket 7 to tension the soiled towel web. The upper portion of the vertical plate 11 is provided with a forwardly extending plate 18, the outer end of which is curved upwardly to lie between the feed and 40 take-up rolls respectively indicated by 19—20. The swing-housing thus formed is pivoted by suitable means indicated at 10, the pivot being arranged near the top of the outer casing 2. This housing supports the entire mechanism of 45 the present invention. After the door 3 of the casing 2 is open, the housing can be swung outwardly to facilitate introduction of fresh toweling and/or removal of soiled toweling.

After introduction of a roll of clean toweling 50 14 the end of the toweling is first engaged with the feed roll 19, fixed to a shaft 21 rotatably journaled in the plates 8 and 9. The journal detail is best shown in Fig. 3. The toweling is then brought around a pinch roll 22 journaled in slots 23 of the plates 8 and 9. This roll operates to press the toweling against the feed roll to obtain the proper frictional contact. The toweling is then brought downwardly through a slot 25 and below the bottom of the swing-housing and then upwardly to form a loop indicated at 26, and is then brought upwardly around the beveled edge 16 and the tensioning bracket 7 and then upwardly over a flap 27 secured to a cross shaft 28, which is journaled in the side 65 plate members 8 and 9, and then to the soiled towel roll 29. The shaft of this roll is suitably guided in slots 31 in the plates 8 and 9, and the roll rests by gravity upon and is frictionally driven by the take-up roll 20.

70 An important feature of this invention relates to means adapted to be automatically conditioned during towel dispensing operation for subsequently automatically rotating the take-up and feed rolls. One embodiment of this feature includes 75 an auxiliary shaft 35 mounted parallel to the

feed and take-up rolls 19 and 20 respectively and equidistant therefrom. The shaft 35 is journaled in a sleeve 36 which in turn is journaled at one end in the side plate member 9 of the swing-housing as shown in Fig. 3. The sleeve 36 has 5 formed integral therewith a ratchet wheel 37 having clutch teeth 38 adapted to mesh with complementary clutch teeth 39 of the comparatively large clutch gear 41 which is slidably mounted on the shaft 35. This clutch gear 41 10 is at all times in mesh with the gear 42 secured to the shaft 21 of the feed roll 19 and also with the gear 43 secured to the shaft 44 of the take-up roll 20, thus providing a gear train providing means for rotating the feed and take-up rolls 15 simultaneously and at equal speeds as shown in Fig. 2. Clutch teeth 45 are provided on the outer face of the clutch gear 41 and are adapted to mesh with complementary clutch teeth 46 of the member 47 which is secured to the outer end of 20 the shaft 35. The coiled compression spring 48 normally tends to keep the clutch gear 41 and the member 47 in clutching engagement.

A torsion spring 51 is mounted on the sleeve 36 and has one end secured thereto as at 52. 25 The other end of the spring 51 is secured to the wall 8 of the swing-housing as indicated at 53. Mounted loosely on an eccentric 54 on the shaft 44 of the take-up roll 20 is a dog 55 having a hook member 56 adapted to engage the 30 ratchet teeth of the member 37 (Fig. 8). The tension spring 57 acts to hold the hook member 56 constantly in grabbing relation with the ratchet teeth. Thus it will be noted by reference to Fig. 2 that as a pull is exerted on the towel 35 web the gear train 42—41—43 is actuated, each gear rotating in the direction of its indicating arrow as shown in full lines. Upon rotation of the take-up roll shaft 44 the dog 55 is given an oscillatory movement forwardly from the position shown in Figs. 2 and 8 and thus rotating the ratchet wheel 37 in a counter-clockwise direction or the same direction of rotation as the feed and take-up rolls. For each rotation of the take-up roll 20 the ratchet wheel is rotated 45 a distance equal to the oscillatory throw of the eccentric 54, in the present instance a distance of two teeth. As the ratchet wheel 37 is rotated the spring 51 is gradually put under tension, it having one end secured to the sleeve 36 which 50 is integral with the ratchet 37 and the other end secured to the wall of the swing-housing. A latch 59 mounted adjacent the periphery of the ratchet wheel 37 has a detent normally engaging the ratchet teeth and thus enabling the 55 spring to be put under tension gradually at each revolution of the take-up roll.

It will be noted by reference to Fig. 2 that as the ratchet wheel 37 is rotated in a counter-clockwise direction and the spring put under tension 60 that the stored up energy in the spring 51 is gradually exerting a greater and greater force to move the ratchet wheel in a clockwise direction or the same direction as the rotation of the clutch gear 41 under normal operation 65 of the cabinet. To release this energy and utilize the same to rotate the clutch gear 41 and likewise the gear 42 and 43 of the feed and take-up rolls respectively when the roll of clean toweling is exhausted is the function of the mechanism now to be described.

A drop bar 61 is slidably mounted on the side plate member 9 by means of the screws 62 and vertical slots 63. The drop bar 61 is normally retained in the raised position shown in Fig. 2 75

by means of a bell crank 65 having an upstanding arm 66 terminating in a right angled lug 67 which traverses the horizontal slot 68 of the drop bar 61 and upon which the drop bar is seated. The bell crank 65 is loosely mounted upon the transverse shaft 71 which is rotatably journaled in the plates 8 and 9 adjacent the horizontal clean towel roll supporting bottom 12. It will be noted by reference to Fig. 2 that the lug 67 is positioned slightly over the center to the left of the shaft 71 thus preventing accidental displacement of the drop bar 61. A trip arm 73 is secured to the shaft 71 preferably in the center thereof as shown in Fig. 6 and is adapted to rest against the clean towel roll 14. A spring 74 provides positive means for holding the trip arm 73 in contact with the clean towel roll. Externally of the side plate 8 and adjacent the bell crank 65 is an arm 75 also secured to the shaft 71. As the clean roll diminishes the trip arm 73 moves downwardly and likewise the arm 75 until they assume the positions shown in Fig. 5 wherein the roll of clean toweling is practically exhausted. The bell crank 65 has a forwardly extending arm 77 terminating in a right angled lug 78 which lies in the path of the arm 75. It will also be noted that the trip arm 73 has a downwardly extending portion 79 as viewed in Fig. 5 having an edge which contacts with the clean towel web adjacent the forward edge 81 of the false bottom 12. This portion 79 may be of substantially less width than the towel web and the tension of the web and the proximity of the edge of the portion 79 to the edge 81 prevents further drop of the trip arm until the clean toweling is entirely exhausted. When the end of the towel passes the contacting edge of the trip arm 73 the trip arm falls to the position shown in Fig. 7, the arm 75 which is also secured to the shaft 71 strikes against the lug 78 of the bell crank 65 thus moving the supporting lug 67 which traverses the slot 68 of the drop bar over the center to the right of the shaft 71 whereupon the drop bar 61 will fall. As the drop bar 61 falls a beveled cam lug 83 secured to the drop bar 61 moves the yoke member 85 from the position shown in Fig. 3 to the position shown in Fig. 4. The yoke member 85 is pivotally mounted as at 86 to the side plate member 9. A pair of rollers 87 are mounted on the yoke member 85 and are adapted to bear against the outer face of the clutch member 41. A lateral extension 88 of the yoke member 85 extends rearwardly and lies in the path of the cam lug 83 as shown. The drop bar 61 is also provided at its upper end with a lateral extension 91 adapted to strike against the arm 92 of the dog 55 thus moving the hook 56 out of engagement with the ratchet teeth of the member 37. Simultaneously the arm 93 of the dog 55 moves into engagement with the latch 59 and moves it out of engagement with the member 37. The drop bar 61 having moved the clutch member 41 into engagement with the ratchet member 37 by means of the yoke member 85 and the locking dogs having been moved out of engagement with the ratchet teeth of the member 37 the stored up energy of the spring 51 is now utilized to rotate the member 37 and likewise the clutch member 41 in a clockwise direction and thus operate the feed and take-up rolls 19 and 20 to draw the depending loop and unused end of the towel within the cabinet so that the entire length of toweling will be wound upon the soiled towel roll and may be thus removed by the attendant with no waste of time.

A means for visible indication of the approximate amount of clean toweling still remaining in the cabinet is provided by a segment 95 pivoted as at 96 and having suitable indicia on its periphery as at 97. An arm 98 secured to the pivot shaft 96 is connected to the arm 75 by means of the rod 99. As the arm 75 and the trip arm 73 move together as the roll of clean toweling diminishes the segment 95 will be rotated in like manner. An aperture 101 in the door 3 is provided for noting the reading on the segment 95. Thus, the indicator is operated by the same trip mechanism which winds up the end of the towel and the gradual descent of the trip mechanism to its operative position gradually moves the indicator to show the approximate amount of clean toweling left in the cabinet.

Means are provided for locking the rolls against rotation should a maliciously inclined person cut the towel web and attempt to withdraw the toweling from the cabinet. Such means are shown in Figs. 1, 6, 10 and 11 wherein the cross shaft 28 is provided with a depending flap 27 which assumes the position shown in Figs. 1 and 10 during the normal towel dispensing period. An arm 102 is secured to the shaft 28 externally of the side plate 8 and assumes the position shown in Fig. 10 during normal operation of the cabinet. The ratchet 103 is shown formed integral with the usual ratchet 104 which is secured to the shaft 44 of the take-up roll 29. The usual dog 105 prevents backward rotation of the take-up roll. Should the web of toweling be cut the tension of the toweling is released to allow oscillation of the flap 27 which will assume the position indicated in Fig. 11, being moved to such position because of the weighted arm 102 which is secured to the shaft 28. The arm 102 has an offset portion 108 which is adapted to engage the teeth of the ratchet 103 and thus positively prevent further rotation of the take-up roll and consequently the feed roll which is at all times in driving engagement with the take-up roll. Thus it will be impossible to withdraw toweling by pulling on the soiled towel web because of the locking arm 102.

The towel cabinet herein disclosed also includes a stop mechanism adapted to be automatically released, i. e., the rotation of the feed and take-up rolls are stopped after the delivery of a length of toweling such as by the pulling of the clean toweling. Subsequently, after a suitable time interval, the stop mechanism is automatically actuated to release the rolls for further dispensing of a length of toweling. Such mechanism is shown in Figs. 3, 6 and 10 wherein a segmental gear 111 having a hub 112 journaled in the side plate member 8 is secured to the end of the shaft 35 by means of pin 113. Thus the shaft 35 and the segmental gear rotate together, as shown in Fig. 3. A sliding bolt 114 adapted to be translated in the bore 115 of the gear 111 is held against displacement by the pin 116. Mounted upon the side plate 8 and below the segmental gear 111 is a suitable timing element such as a dash pot 117 having a plunger 118 having secured thereon an upstanding lug 119 adapted to move against the translatable bolt 114 as shown in Figs. 3 and 10. The plunger 118 has an extension 121 slidably carried by the guide plate 122. Suitable rack teeth 123 are provided upon the extension 121 adapted to be engaged by the teeth of the segmental gear 111. As viewed in Figs. 2, 3 and 10 pulling on the web of clean toweling actuates the gear 42 of the feed roll which in turn rotates 75

the clutch gear 41 thus rotating the shaft 35 and segmental gear 111 in the direction of the arrow as shown in Fig. 10. It will be noted that there are approximately twice as many teeth on the clutch gear 41 as on the gears 42 and 43 of the feed and take-up rolls respectively. Thus one revolution of the feed roll will rotate the clutch gear 41 and thus the shaft 35 and segmental gear 111 one-half revolution. Rotation of the segmental gear 111 moves the teeth into engagement with the rack teeth 123 of the extension 121, thereby moving the lug 119 to the dotted line position shown in Fig. 10 and the gear 111 will continue rotation until the bolt 114 which extends beyond the periphery of the gear 111 strikes against a suitable stop 125. The lug 119 will then slowly travel in the direction of the dotted arrow being actuated by the spring 126 and held against too rapid movement by means of the dash pot 117. The lug 119 moves against the translatable bolt 114 and moves it out of engagement with the stop 125 whereupon the rolls are again free to rotate and the cabinet is again conditioned for dispensing another length of toweling.

25 The foregoing described automatic lock and release mechanism is disclosed in my Patent 1,988,-266 issued January 15, 1935, and is not claimed per se in this application.

I claim as my invention:

30 1. In a towel dispensing apparatus, a cabinet, a feed roll and a take-up roll mounted therein, gears on said rolls, an intermediate gear constantly in mesh with said gears whereby said rolls are rotated simultaneously when a pull is exerted upon the clean toweling, a shaft upon which said intermediate gear is loosely mounted, means releasably and operatively connecting said intermediate gear to said shaft, a sleeve surrounding said shaft, a spring connected to said sleeve, means operated by rotation of said rolls to wind up said spring including means by which the intermediate gear is connected to rotate the shaft, and means operative when the supply of clean toweling is substantially exhausted to disconnect said intermediate gear from said shaft and connect it to said sleeve, whereby said wound up spring will rotate said intermediate gear independently of any pull upon the clean towel to rotate said rolls.

50 2. In a towel dispensing apparatus, a cabinet, a feed roll and a take-up roll mounted therein, gears on said rolls, an intermediate gear constantly in mesh with said gears whereby said rolls are rotated simultaneously when a pull is exerted upon the clean toweling, a shaft upon which said intermediate gear is loosely mounted, a sleeve surrounding said shaft, clutch members on opposite faces of said intermediate gear, clutch members on said shaft and said sleeve, means normally maintaining one of said clutch members on said intermediate gear in operative relation to the clutch member on said shaft, and automatic means operative when the supply of clean toweling is substantially exhausted to disconnect the clutch member on said shaft from one of said clutch members on said intermediate gear and to connect the clutch member on said sleeve to the other of said clutch members on said intermediate gear.

70 3. In a towel dispensing apparatus, a cabinet, a feed roll and a take-up roll mounted therein, means connecting said rolls for rotation one by the other when a pull is exerted upon the clean toweling, automatic means operative when the clean toweling is substantially exhausted to ro-

tate said rolls independently of any pull upon the clean toweling, said automatic means including a control member moving gradually to operative position as the supply of clean toweling diminishes, and indicating means operated by said control member for indicating the quantity of clean toweling in said cabinet.

4. In a towel dispensing apparatus, a cabinet, a feed roll and a take-up roll mounted therein, means connecting said rolls for rotation one by the other when a pull is exerted upon the clean toweling, automatic means operative when the clean toweling is substantially exhausted to rotate said rolls independently of any pull upon the clean toweling, said automatic means including a control member moving gradually to operative position as the supply of clean toweling diminishes, and indicating means operatively connected to said control member and actuated by movement of said control member to indicate the quantity of toweling in said cabinet.

5. A towel dispensing apparatus, including a feed roll, and a take-up roll, a shaft having a sleeve rotatable thereon, a spring and means connecting it to shaft and sleeve to be wound when the sleeve is rotated, driving elements for said feed and take-up rolls, including an element rotatable and slidable on said shaft, and means by which said slidable element is adapted to be alternately operably connected with the shaft or 30 sleeve respectively to drive the shaft or to be driven by the sleeve, releasable means by which the take-up roll operates the sleeve to partly wind the spring at each operation of the roll, releasable means to hold the sleeve against movement 35 by the spring, and means operable when the toweling supply is substantially exhausted for causing the slidable element to be slid to operable connection with the sleeve and to release said releasable sleeve-operating means and said sleeve holding means to allow power applying action 40 of the spring.

6. A towel dispensing apparatus including a feed roll and a take-up roll, a shaft having a sleeve rotatable thereon, a spring and means connecting it to shaft and sleeve to be wound when the sleeve is rotated, a gear train connecting said feed and take-up rolls comprising only three spur gears one rotatable and slidable on said shaft, means by which said slidable gear is adapted to 50 be alternately operably connected with the shaft or sleeve respectively to drive the shaft or to be driven by the sleeve, releasable means by which the take-up roll operates the sleeve to partly wind the spring at each operation of the roll, releasable means to hold the sleeve against movement 55 by the spring, and means operable when the toweling supply is substantially exhausted for causing the slidable gear to be slid to operable connection with the sleeve and to release said releasable sleeve-operating means and said sleeve holding means to allow power applying action of the spring.

7. A towel dispensing apparatus including, a feed roll and a take-up roll, a shaft having a 65 sleeve rotatable thereon, a spring and means connecting it to shaft and sleeve to be wound when the sleeve is rotated, a gear train connecting said feed and take-up rolls comprising spur gears one rotatable and slidable on said shaft, means by 70 which said slidable gear is adapted to be alternately operably connected with the shaft or sleeve respectively to drive the shaft or to be driven by the sleeve, releasable means by which the take-up roll operates the sleeve to partly wind the spring 75

at each operation of the roll, releasable means to hold the sleeve against movement by the spring, and means operable when the toweling supply is substantially exhausted for causing the slidable gear to be slid to operable connection with the sleeve and to release said releasable sleeve-operating means and said sleeve holding means to allow power applying action of the spring.

8. A towel dispensing apparatus including, a feed roll and a take-up roll, a shaft having a sleeve rotatable thereon, stop and timing mechanism controlled by and controlling said shaft to limit the amount of towel dispensing, a spring and means connecting it to shaft and sleeve to be wound when the sleeve is rotated, a gear train connecting said feed and take-up rolls comprising only three spur gears one rotatable and slidable on said shaft, means by which said slidable gear is adapted to be alternately operably connected with the shaft or sleeve respectively to drive the shaft or to be driven by the sleeve, releasable means by which the take-up roll operates the sleeve to partly wind the spring at each operation of the roll, releasable means to hold the sleeve against movement by the spring, and means operable when the toweling supply is substantially exhausted for causing the slidable gear to be slid to operable connection with the sleeve and to release said releasable sleeve-operating means and said sleeve holding means to allow power applying action of the spring.

9. A towel dispensing apparatus having measuring and take-up rolls each having a drive gear, a shaft having a gear shiftable thereon which gear is constantly in mesh with the drive gears of the rolls, a ratchet wheel rotatable on the shaft a spring which is wound by said ratchet wheel to store power to subsequently drive said ratchet wheel, means operated by one of the rolls for rotating the ratchet wheel step by step to totally wind the spring by the time the clean toweling supply is substantially exhausted including a pawl, clutch means by which the shift gear can be alternately coupled with the shaft and ratchet wheel, and means controlled by the toweling and automatically operable when the clean towel supply is substantially exhausted to

release the pawl and shift the shiftable gear to couple the same with the ratchet wheel.

10. A towel dispensing apparatus having measuring and take-up rolls each having a drive gear, a shaft having a gear shiftable thereon which gear is constantly in mesh with the drive gears of the rolls, a ratchet wheel rotatable on the shaft a spring which is wound by said ratchet wheel to store power to subsequently drive said ratchet wheel, means operated by one of the rolls for rotating the ratchet wheel step by step to totally wind the spring by the time the clean toweling supply is substantially exhausted including a pawl, clutch means by which the shift gear can be alternately coupled with the shaft and ratchet wheel, and means controlled by the toweling and automatically operable when the clean towel supply is substantially exhausted to release the pawl and shift the shiftable gear to couple the same with the ratchet wheel, and a stop mechanism controlled by and controlling said shaft.

11. A towel dispensing apparatus having measuring and take-up rolls, means driving said rolls in unison including shiftable means constantly in roll-driving relation, power storing means, means by which said shiftable means operates the power storing means to store power, means operable by said shiftable means to drive the take-up roll when said shiftable means is shifted, a pawl which is released to allow the stored power to drive said take-up roll, and means operated by the toweling when the clean toweling supply is substantially exhausted to shift said shiftable means and release said pawl.

12. A cabinet having clean towel dispensing means and soiled towel take-up means, and means by which one operates the other, means putting a frictional drag on the soiled toweling to put it under tension as it approaches the take-up means, and detent means for preventing reverse action of said take-up means including a pawl which is held from detent position by the tensioned soiled toweling, said pawl being adapted to assume detent position when towel tension ceases.

ROMAIN DE BERSAQUES.
